UNITED STATES PATENT OFFICE.

JOHN BIZET, OF NEW YORK, N. Y.

COMBINATION ASH-SIFTER AND COAL-BIN.

1,323,000.

Specification of Letters Patent. Patented Nov. 25, 1919.

Application filed March 7, 1917. Serial No. 153,082.

To all whom it may concern:

Be it known that I, JOHN BIZET, a citizen of the United States, residing at New York, in the county of New York, State of New York, have invented a new and useful 5 Combination Ash-Sifter and Coal-Bin; and I do hereby declare the following to be a full, clear, and exact description of the invention, such as will enable others skilled in 10 the art to which it appertains to make and use the same.

This invention relates to an improved combination ash sifter and coal bin, and one of the objects of the invention is to provide 15 an improved device of this kind having an ash sifter which may be rocked or rotated for sifting the ashes.

A further object of the invention is to provide a sifting member which may be 20 bodily removed from its supporting receptacle.

A further object of the invention is to provide a closure having a bearing for one of the pintles (which has a crank) of the 25 sifter, and constituting means to support one end of the sifter.

A further object of the invention is the provision of a casing divided into two compartments, one for the reception of the 30 sifter, the other for the reception of coal, and in which other compartment, a suitable draining false bottom is arranged, whereby when dampening or wetting the coal, the water may be drained off.

35 In practical fields, the details of construction may necessitate alterations falling within the scope of what is claimed.

The invention comprises further features and combination of parts, as hereinabove set forth, shown in the drawings, and 40 claimed.

In the drawings:—

45 Figure 1 is a view in perspective of the combination ash sifter and coal bin, constructed in accordance with the invention.

Fig. 2 is a cross sectional view on line 2—2 of Fig. 1.

Fig. 3 is a cross sectional view on line 3—3 of Fig. 1.

50 Fig. 4 is a longitudinal sectional view on line 4—4 of Fig. 1.

Fig. 5 is a horizontal sectional view on line 5—5 of Fig. 1.

55 Referring more especially to the drawings, 1 designates a suitable casing which

may be of any suitable shape or configuration, preferably rectangular, and provided with a top portion inclined from the rear downwardly toward the front, said casing to be constructed of any suitable material. 60 This casing 1 has a vertical partition 2 dividing the casing into two compartments 3 and 4, a sifter holding compartment and a coal receiving compartment. Arranged in the coal receiving compartment 4 is a false 65 bottom 5 having perforations 6 and provided with marginal downwardly extending flanges 7 whereby the false bottom is supported spaced from the bottom proper of the casing. The bottom proper 8 of the coal compartment is provided with drain cock 9, for draining off the water, which is used for dampening the coal which makes the coal burn better. The openings 10 and 11 of 70 said compartments 3 and 4 are covered by 75 the closures 12 and 13, which are hinged at 14 adjacent the rear upper part of the casing and which closures are provided with handles 15 and 16. The compartment in the front wall of the casing has an opening 80 17, which is covered by the closure 18 hinged at 19. The closure 18 is provided with hooks 20 to enter the eyes 21, whereby the member 18 may be held securely closed. Said closure 18 has a handle 22, and is provided with a bearing 23. The rear wall of 85 the casing adjacent the compartment 3 has a screw 24 threaded therein, which screw is provided with a socket 25. A suitable sifter 26 is arranged in the compartment 3. The 90 sifter is elongated, and rectangular in cross section. Owing to this rectangular construction, the ashes are thoroughly agitated, since they are thrown from one side to the other of the several faces of the sifter, whereby the dust of the ashes may be thoroughly 95 separated from the cinders. In other words as the cinders are tossed or beaten from one face of the sifter to the other, as the sifter is rotated at a moderate speed, the dust becomes thoroughly dislodged from the cinders. This sifter is substantially elongated and rectangular in shape, and is provided with solid or closed ends 27 and 28, and the wire fabric longitudinal sides 29 and a similar bottom 30. The closure of the sifter consists of a frame 31 hinged at 32 and provided with a latch 33, and is covered with a wire fabric 34. The solid end 28 of the sifter has a pintle 35 engaging the socket 25 100 105 110

of said screw 24. The end 27 of the sifter has a pintle 36, which engages the bearing 37 of the upper edge of the opening 17 and in the bearing 23 of the closure 18, whereby the sifter may be supported in the compartment 3. The pintle 26 has a shoulder 39, which engage the front wall of the compartment 3 adjacent the bearing 37, thereby preventing excessive axial movement of 10 the sifter. A crank 40 is carried by the pintle 36, whereby the sifter may either be rocked or rotated. An ash receiving pan 41 is arranged in the bottom of the compartment 3. When sifting ashes, the same may 15 be deposited in the sifter while in its compartment by opening the closure 12, then by turning or rocking the crank, the ashes may be sifted, the ashes proper falling into the pan 41, while the cinders remain in the 20 sifter. It is to be noted that by means of the closure 18, the sifter is removably supported in its receptacle. By opening the closure 18, the sifter may be removed for emptying the cinders.

25 The invention having been set forth, what is claimed as new and useful, is:—

In an ash sifter, the combination with a casing having a compartment, the lower part of the front wall of the compartment

having an opening, the lower end of the 30 wall above said opening having a bearing, the rear wall of the compartment having an adjustable socket member, an elongated revoluble sifter having a pintle at one end engaging said socket member, the other end of 35 the sifter having a pintle provided with a shoulder and designed to engage the bearing in the lower edge of the wall above the opening in said wall, whereby as the socket member is adjusted said shoulder will engage the inner face of the wall adjacent the opening, and a hinged closure for the opening which, when opened, will permit the removal of the sifter through the opening, the 40 upper edge of the closure for the opening 45 having a bearing to coöperate with the bearing in the lower edge of the wall above the opening to retain the shoulder pintle in place, and a crank for said pintle so that the sifter may be rotated.

50 In testimony whereof I have signed my name to this specification in the presence of two subscribing witnesses.

JOHN BIZET.
